UNITED STATES PATENT OFFICE

167,143

DISPLAY BOARD OR SIMILAR ARTICLE

Jack J. Greitzer, Cleveland, Ohio, assignor to The Bingham-Herbrand Corporation, Fremont, Ohio, a corporation of Ohio

Application February 23, 1952, Serial No. 18,648

Term of patent 14 years

(Cl. D80—1)

To all whom it may concern:

Be it known that I, Jack J. Greitzer, a citizen of the United States and resident of Cleveland, in the county of Cuyahoga and State of Ohio, have invented a new, original, and ornamental Design for a Display Board or Similar Article, of which the following is a specification, reference being had to the accompanying drawing, forming a part thereof.

In the drawing, Fig. 1 is a front view of a display board, showing my new design; Fig. 2 is a top plan view thereof; Fig. 3 is a section taken on the line 3—3 of Fig. 1, and Fig. 4 is a section taken on the line 4—4 of Fig. 1.

I claim:

The ornamental design for a display board or similar article, substantially as shown.

JACK J. GREITZER.
